CONVERTIBLE AND ADJUSTABLE ARTICLE CARRIER

John E. Kalske, Washington, D. C.

Application October 8, 1943, Serial No. 505,529

10 Claims. (Cl. 224—16)

This invention relates to article carriers and more particularly to belt or strap carriers for boxes, tool chests, purses, knapsacks or the like, which are conveniently convertible from a shoulder sling suspension to hand-grips of different sizes for such articles.

It is the object of the present invention to provide a belt or strap support for articles of diverse nature which is capable of quick and convenient adjustment to attain different modes of support of the article by the same belt while utilizing the complete length of the belt in order to render the arrangement of pleasing appearance.

It is a further object of the invention to provide a shoulder sling suspension for articles such as tool chests, boxes and the like which may be supported from the shoulder and which may be readily converted into a conventional support simulating a hand-hold provided by a conventional handle on such articles.

Other objects and purposes will appear from the following more detailed description of the invention, taken in conjunction with the accompanying drawing, wherein

Fig. 1 is a perspective view of a carpenter's tool chest embodying the present invention in position to be carried in a manner similar to that afforded by a conventional handle;

Fig. 2 is a perspective view of the upper portion of the tool chest showing the position of the parts when the article carrier is arranged to form a shoulder sling by which the tool chest may be carried;

Fig. 3 is a perspective view of a second embodiment of the invention showing a purse embodying a strap support in position to be used as a shoulder sling; and

Fig. 4 is a front elevation of a portion of the purse shown in Fig. 3 in which the strap is crossed in four layers to form a hand-hold therefrom, and illustrating the capability of the loop of the strap to assume intermediate positions between those shown in Figs. 3 and 4 as the strap is arranged in two or three layers.

In Fig. 1 a tool chest A is illustrated having the article carrier in accordance with the present invention applied thereto adjacent to the upper wall B thereof. This tool chest may be of the construction illustrated in Fig. 1, or may assume the specific construction shown in my application Serial No. 473,646, filed January 26, 1943, Patent No. 2,332,918, October 26, 1943.

In the transport of such tool chests it is desirable that at times the same be carried by a han-

dle which may be applied to the wall B thereof as is common in the art of luggage and analogous articles. On the other hand, at other times it is desirable that the tool chest be supported by a sling passing over the carrier's shoulder. It is the aim of the present invention to provide a belt or strap support which is easily convertible from one type of support to the other at no substantial increase in cost of the handle construction.

As shown in Figs. 1 and 2, the strap 6 is adapted to be fixedly attached to one end 1 of the tool chest by rivets, staples, tacks or the like, which strap may be of any width and may be made of any material such as leather or fabric. A fastening means is attached to the other end of the strap 6 at 2 in a manner similar to the attachment 1, and the fastening means may assume the form of a buckle 4 comprised by a pair of ring-like or link frames 4a and 4b which are adapted to be engaged by the free end of the strap 6 to attain a fastening thereof. Such buckle fastenings are known in the prior art, and other types of buckles may be used which permit an alternative looping therethrough as well as a fastening thereat, for example, those embodying sliding jaws which engage the belt at the time of fastening thereof.

Additional fastening means 3 comprised of a pair of links 3a and 3b are also provided adjacent to the fixed end of the belt 1 which may be confined between a pair of rows of stitching on belt 6, and which may be selectively employed to engage the free end of the belt after the same is first threaded through guides 5 mounted on the top wall B of the case, looped through one or both rings 4a and 4b of the buckle 4 and then looped back through the guides 5 in layer 6b until the free end of the belt is fastened between the rings 3a and 3b. Any other type of buckle may be used in lieu of clasp 3. The belt is of such length that the formation of the two plies 6a and 6b leave a sufficient length at the end 6c for engagement with the buckle or clasp 3 while forming a sufficient bulge 6d between the guides 5 to provide a conventional hand-hold similar to a conventional handle at the center of the tool chest.

The article carrier in accordance with the invention as applied to the tool chest shown in Figs. 1 and 2 may be as well applied to articles of all types, including bags, purses, chests, and the like, and a wider range of adjustment of the size of the belt loop may be obtained by the provision of buckles constituted by three links or rings instead of merely two. Such an arrange-

ment is shown applied to a money purse or ladies' handbag *P* in Fig. 3 wherein one end of the belt *11* is fixedly attached to the purse at the end *11a* by one or more suitable rivets or other fastening means, while the opposite end of the belt *11e* may be guided through one or more of the clasp rings *8a*, *8b* and *8c* forming part of a buckle device *8* attached to the opposite end of the article, while a similar three-ring buckle *7*, constituted by rings *7a*, *7b* and *7c*, is provided adjacent the point of attachment of the belt to the article. Thus, in Fig. 3 the belt *11* is shown arranged to be worn as a shoulder sling of maximum length by the engagement of the free end of the belt *11e* by at least two of the rings, such as *8b* and *8c*, or by *8a* and *8b*, or by *8a* and *8b* together cooperating with ring *8c*.

The other extreme of arranging the belt to provide a hand-hold rather than a shoulder sling support is shown in Fig. 4, wherein the belt is arranged in four plies and the first ply *11a* shows the belt looped through the ring *8c*, followed by the return of the ply *11b* and the looping thereof through the ring *7c* of clasp *7* followed by the course of the third layer *11c* which is looped through one or both of the remaining rings *8a* and *8b* of the clasp *8* followed by the formation of the fourth layer *11d* which terminates in the engagement of the free end *11e* between the rings *7a* and *7b*.

Loops of intermediate extent may be formed by arranging the belt in two or three plies in addition to one and four plies alternatively with one another, or with each other. Thus, the belt may be extended from the end *11a* through the ring *8c* and may be guided through one or more of the rings of the clasp *8* for engagement of the free end *11e* between the rings *8a* and *8b* of the clasp *C* to obtain three plies of the belt.

Alternatively two plies of the belt may be attained in a manner similar to that shown in Fig. 1 by looping the belt through one or more of the links of the clasp *8* and engaging the free end of the belt through two or more of the rings of clasp *7*, such as rings *7a* and *7b*, *7b* and *7c*, or *7a* and *7b* together cooperating with ring *7c*.

Of course, additional plies and ranges of variation may be attained by the provision of more rings in the respective clasps or buckles at the opposite ends of the buckle. The rings may assume the form of elliptical links or closed frames as shown in Fig. 1, circular rings as shown in Fig. 3, or may be formed of other contours being curved in part and straight in other parts. The belts or straps may be in the form shown in the drawing, or may be cylindrical or of any other desired cross-section and these may be formed of any flexible materials known in the art, such as textile fabrics, leather or plastics. If desired, when the belt is of textile material, the end thereof may be rigidified by dipping in a hardenable medium such as varnish or hot lead which is subsequently hardened in order to facilitate the guiding thereof through the several loops of the assembly.

While I have described my invention as embodied in a specific form and as operating in a specific manner for purposes of illustration, it should be understood that I do not limit my invention thereto, since various modifications will suggest themselves to those skilled in the art without departing from the spirit of my invention, the scope of which is set forth in the annexed claims.

I claim:

1. A receptacle carrier comprising a belt having one end thereof attached to the receptacle, a combined guide and fastening means for the opposite end of the belt attached to the receptacle at a point spaced from the belt attachment, and additional fastening means for the free end of the belt in proximity to the fixed end of the belt attachment whereby the free end of the belt may be selectively engaged by said first-mentioned fastening means to form a large loop by the belt or may be guided through said first-mentioned means for engagement with said additional fastening means to form a smaller loop by the to-and-fro course of said belt.

2. A receptacle carrier comprising a belt having one end thereof attached to the receptacle, a combined guide and fastening buckle for the opposite end of the belt attached to the receptacle at a point spaced from the belt attachment, and additional fastening means comprising a second buckle for the free end of the belt in proximity to the fixed end of the belt attachment whereby the free end of the belt may be selectively engaged by said first buckle to form a large loop by the belt or may be guided through said first buckle for engagement with said second buckle to form a smaller loop by the to-and-fro course of said belt.

3. A receptacle carrier comprising a belt having one end thereof attached to the receptacle, fastening means for the opposite end of the belt comprising a plurality of ring-like frames attached to the receptacle at a point spaced from the belt attachment, and additional fastening means comprising a plurality of ring-like frames for the free end of the belt in proximity to the fixed end of the belt attachment whereby the free end of the belt may be selectively looped through some of said ring-like frames and engaged by the others to interchangeably utilize the belt as a shoulder sling or as a hand-hold for the receptacle.

4. A receptacle carrier comprising a belt having one end thereof attached to the receptacle, a plurality of clasp rings adapted to operate as a fastening means for the opposite end of the belt attached to the receptacle at a point spaced from the belt attachment, and an additional set of clasp rings for the free end of the belt in proximity to the fixed end of the belt attachment whereby the free end of the belt may be selectively engaged by said first-mentioned clasp rings to form a large loop by the belt or may be passed through said first-mentioned clasp rings for engagement with said additional set of clasp rings to form a tighter loop by the to-and-fro course of said belt.

5. A carrier for a tool chest comprising a strap having one end thereof attached to the article at one wall thereof, combined guide and fastening means attached to the article at a point spaced remotely from the strap attachment and adjacent to said one wall of the article, additional fastening means for the free end of the strap in proximity to the fixed end of the strap attachment whereby the free end of the strap may be selectively engaged by said first-mentioned fastening means to form a large loop of the strap to operate as a shoulder sling suspension for the tool chest, or may be guided through said first-mentioned fastening means for engagement with said additional fastening means to form a tight loop by the to-and-fro course of said strap and to form a convenient hand-hold by said strap.

6. An article carrier comprising a strap having one end thereof attached to the article at one wall thereof, loop fastening means attached to the article at a point spaced remotely from the strap attachment and adjacent to said one wall of the article, additional fastening means for the free end of the strap in proximity to the fixed end of the strap attachment whereby the free end of the strap may be selectively engaged by said first-mentioned fastening means to form a large loop of the strap, and a pair of spaced guides in said wall of the article adapted to have the strap passed therethrough, through the loop of said first-mentioned means and then back through said guides to bring the free end of said strap into engagement with said additional fastening means to form a tight loop by the to-and-fro course of said strap and to form a convenient hand-hold of said strap between said guides.

7. An article carrier comprising a belt having one end thereof attached to the article, three clasp rings attached to the article at a point spaced from the belt attachment and a guide ring in proximity to the fixed end of the belt attachment whereby the free end of the belt may be selectively guided through one of said first-mentioned rings and engaged by the other two following the looping of the belt through said guide ring to form a hand-hold by the triple course of the belt or may be engaged by a pair of said first-mentioned rings to form a large loop acting as a shoulder support.

8. An article carrier comprising a belt having one end thereof attached to the article, three clasp rings attached to the article at a point spaced from the belt attachment and an additional set of a plurality of clasp rings in proximity to the fixed end of the belt attachment whereby the free end of the belt may be selectively engaged by a pair of said first-mentioned clasp rings to form a large loop by the belt, or may be passed through at least one of said first-mentioned clasp rings for engagement with a pair of clasp rings of said additional set to form a smaller loop by the to-and-fro course of said belt, or may be selectively guided through one of said first-mentioned rings and engaged by the other two following the looping of the belt through at least one of said additional set of clasp rings to

form a still smaller loop by the triple course of said belt.

9. An article carrier comprising a belt having one end thereof attached to the article, three clasp rings attached to the article at a point spaced from the belt attachment and an additional set of three clasp rings in proximity to the fixed end of the belt attachment whereby the free end of the belt may be selectively engaged by a pair of said first-mentioned clasp rings to form a large loop by the belt, or may be passed through at least one of said first-mentioned clasp rings for engagement with a pair of clasp rings of said additional set to form a smaller loop by the to-and-fro course of said belt, or may be selectively guided through one of said first-mentioned rings and engaged by the other two following the looping of the belt through at least one of said additional set of clasp rings to form a still smaller loop by the triple course of said belt, or may be successively passed through at least one of said first-mentioned rings followed by the passage through one of said additional set and then at least through another one of said first-mentioned rings followed by the engagement of the free end of the belt by a pair of the clasp rings of said additional set to form a still smaller loop by the quadrupled course of said belt.

10. An article carrier comprising a belt having one end thereof attached to the article, a set of a plurality of clasp rings attached to the article at a point spaced from the belt attachment and an additional set of three clasp rings in proximity to the fixed end of the belt attachment whereby the free end of the belt may be selectively passed through at least one of said first-mentioned clasp rings for engagement with a pair of clasp rings of said additional set to form a small loop by the to-and-fro course of said belt, or may be successively passed through at least one of said first-mentioned rings followed by the passage through one of said additional set and then at least through another one of said first-mentioned rings followed by the engagement of the free end of the belt by a pair of the clasp rings of said additional set to form a still smaller loop by the quadrupled course of said belt.

JOHN E. KALSKE.
